UNITED STATES PATENT OFFICE.

EUGÈNE SCHNEIDER, OF LE CREUZOT, FRANCE.

PERCUSSION-FUSE.

1,014,183.

Specification of Letters Patent.

Patented Jan. 9, 1912.

Application filed August 31, 1911. Serial No. 647,050.

To all whom it may concern:

Be it known that I, EUGÈNE SCHNEIDER, of Le Creuzot, Saône-et-Loire, France, have invented a new and useful Improvement in 5 Percussion-Fuses, which is fully set forth in the following specification.

The present invention has reference to a percussion fuse which is provided in the known manner with a safety device comprising 10 loose segments that are held together in the normal condition, or condition of repose, by a peripheral spring and which are intended to separate under the influence of centrifugal force so as to release the plunger 15 or percussion pellet after firing the projectile from the gun.

The invention has for its object a device which is intended to overcome the inertia of the segments and to facilitate at the 20 proper moment their separation under the influence of centrifugal force, the said device also operating to retain the segments in the cocked position, that is to say to prevent them from again coming together when once 25 they have become separated. For this purpose I provide upon a fixed portion of the fuse, tenons or snugs engaging in corresponding grooves in the various segments which are intended to separate under the influence 30 of centrifugal force. These tenons form guiding and driving members for the said segments at the commencement of the action of the centrifugal force but shortly after this force has begun to act, the grooves 35 in the segments during the shifting of the latter toward the periphery escape from the tenons, whereupon the separated segments become independent of the rotary movement of the fuse body and relative circumferential displacement can take place between 40 them and the tenons, so that the latter then come behind a solid portion of the segments and prevent them from again approaching the center; the segments are thus maintained 45 by the tenons in the cocked or displaced position.

In the accompanying drawings I have illustrated the invention applied by way of example to a fuse provided with members 50 for locking the segments both normally and during the acceleration, these members however form no part of the present invention and may be dispensed with in certain cases.

Figures 1 and 2 show the fuse respectively 55 in sectional elevation on the line A A of Fig. 2 and in sectional plan on the line B B

of Fig. 1, the parts being represented in the normal position or positions of repose. Figs. 3 and 4 are similar views showing the parts in the position they occupy while the projectile is moving along the gun barrel. Figs. 60 5 and 6 show the fuse respectively in sectional elevation on the line A A in Fig. 6 and in sectional plan on the line B B in Fig. 5 with the parts in the position they occupy 65 after the projectile has finished its acceleration.

1 designates the fuse body, 2 the striker and 7 the plunger or percussion pellet carrying the priming 13. This plunger is 70 guided in the plug 3 of the base of the fuse and in a socket 8 projecting inwardly from the forward end of the fuse body.

5 designates the segments which in the example shown are four in number; these 75 segments are prevented from moving in either direction lengthwise of the fuse, rearward movement being prevented by the plug 3 and forward movement by the socket 8 and its flange 11 which may form part of an 80 adjustable nut. Normally the said segments are held together in the known manner and engage in a groove 14 in the plunger by the influence of a spring 6 coiled in a peripheral groove 15 in the segments. 85

Projecting from the rear face of the socket 8 and the nut rigidly connected therewith, are tenons 12 corresponding in number to that of the segments 5. Each of these tenons engage in a radial groove 16 in one 90 of the segments. The size of these tenons is slightly less than the radial movement the segments are capable of performing as represented by the distance between their outer edges and the inner wall of the fuse 95 body. It follows from this arrangement that the segments 5 first of all participate in the movement of rotation of the fuse body under the influence of the tenons 12. The known safety devices constituted by the 100 ring 4 for locking the parts in the normal position and by the spring ring 9-10 for locking the parts during the acceleration, release the segments 5 at the end of the acceleration. Centrifugal force then acts instantaneously upon the segments 5 guided by the tenons 12. On separating, the said segments escape from the tenons and immediately perform an angular displacement relatively to the latter and thus assume the position shown in Figs. 5 and 6. The grooves 110 16 being then no longer opposite the tenons

12 the latter prevent the segments from coming together again and also prevent them from impeding the displacement of the plunger 7, if a lateral shock should occur at 5 the moment of impact.

It will be understood that the arrangement described above might be reversed, that is to say, the guidance between the segments and the fuse body might be obtained 10 by means of radial ribs projecting from the segments and escaping from grooves in the socket 8 for example, the subsequent relative displacement preventing unintentional return of the segments toward the center.

15 What I claim and desire to secure by Letters Patent of the United States is:—

1. In a fuse, the combination of a casing or body, a plunger and a percussion cap, a plurality of segments normally locked and 20 engaging said plunger and radially movable under the influence of centrifugal force, a stationary guiding member for each segment having a lateral clearance associated therewith, a corresponding guiding member 25 on each segment and means automatically releasing each segment whereby it moves radially out of engagement with said stationary member and laterally through said clearance out of alignment therewith.

30 2. In a fuse, the combination of a casing or body, a plunger and a percussion cap, a plurality of segments normally locked and engaging said plunger and radially movable under the influence of centrifugal force, a 35 stationary guiding member for each segment between which member and casing there is a clearance, a corresponding guiding member on each segment, and means automatically releasing each segment whereby it 40 moves radially out of engagement with said

stationary member and laterally through said clearance out of alignment therewith.

3. In a fuse, the combination of a casing or body, a plunger and a percussion cap, a plurality of segments normally locked and 45 engaging said plunger and radially movable under the influence of centrifugal force, a stationary guiding member for each segment shorter than the extent of radial movement of said segments and having a lateral clearance associated therewith, a corresponding guiding member on each segment and means automatically releasing each segment whereby it moves radially out of engagement with said stationary member and laterally 50 through said clearance out of alignment therewith.

4. In a fuse, the combination of a casing or body, a plunger and a percussion cap, a plurality of segments normally locked and 55 engaging said plunger and radially movable under the influence of centrifugal force and each of said segments being provided with a guiding groove, a stationary tenon for each segment connected with said casing and engaging in said groove and having a clearance therebetween and said casing, and means automatically releasing each segment whereby it moves radially out of engagement with said stationary member and laterally through said clearance out of alignment therewith. 65

In testimony whereof I have signed this specification in the presence of two subscribing witnesses.

EUGÈNE SCHNEIDER.
